United States Patent Office.

GEORGE B. OWEN, OF WINSTED, CONNECTICUT.

Design No. 2,978, dated March 31, 1868.

DESIGN FOR A CLOCK-CASE FRONT.

The Schedule referred to in these Letters Patent and making part of the same.

TO ALL WHOM IT MAY CONCERN:

Be it known that I, GEORGE B. OWEN, of Winsted, in the county of Litchfield, and State of Connecticut, have invented a new and original Design for a Clock-Case Front; and I do hereby declare that the following is a full, clear, and exact description thereof, which will enable others skilled in the art to make and use the same, reference being had to the accompanying drawings, forming part of this specification.

This invention relates to a new and original design for the front of a wooden clock-case, such as have semicircular or rounded tops. In the accompanying sheet of drawings—

Figure 1 is a front view of a clock-case constructed according to my design.

Figure 2, a horizontal section of the same, taken in the line $y y$, fig. 1.

Similar letters of reference indicate corresponding parts.

A is the base, on which the body; B, of the clock-case rests. This base is of quadrangular form, and its upper edge is rounded, forming a quarter circle, as shown at α in fig. 1. The sides of the case are vertical, and the top of semicircular form, and the edges of the front have a continuous convex bead, b , within which is the door C, the shape of which conforms to the shape of the space within the head b , (see fig. 1.) The opening in the door C, which exposes the dial D, is lined with a metal sash, E, which has taper sides, (see fig. 2,) and a flange, e , at its outer edge, parallel with the face or outer side of the door.

F is a metal sash, with which the opening made in the door to expose the pendulum-bob is lined. This sash is of oval form, as shown in fig. 1, and its shape transversely is shown clearly in Figure 3. A rounded or semicircular top, 3, a concave, 4, at each side, with a plane surface, 5, adjoining, are one concave, and a concave, 6, and plane surface, 7, adjoining, are the other concave. The door G, with the exception of these sashes, is perfectly plain, or free from any ornament.

Having described my invention, what I claim as new, and desire to secure by Letters Patent, is—

The configuration and disposition of the parts, as herein shown and described, to form a new and original design for a clock-case.
